FIG. 1

INVENTOR.

JAN REEF
BY
Burton & Parker
ATTORNEYS

Filed July 24, 1948. Serial No. 7,000. This application is a continuation-in-part of my copending application, Serial No. 579,807, filed February 26, 1945, for a "Gage Frame with Two Opposed Jaws Side-by-Side." The present application is also a continuation-in-part of my copending application, Serial No. 579,808, filed February 26, 1945, for a "Gage Frame with Two Opposed Jaws Side-by-Side."

UNITED STATES PATENT OFFICE

2,562,125

GAUGE

Jan Reef, East Detroit, Mich.

Application March 13, 1948, Serial No. 14,650

1 Claim. (Cl. 33—168)

This invention relates to improvements in gages. The gage of this invention is of that type termed in the trade "go" "no go" gage. It comprises a U-shaped frame the arms of which are provided with opposed gage blades or jaws which project into the U-opening between the arms. At least one of the jaws is adjustable toward and away from the opposed jaw of the other arm to vary the spacing between the jaws. One arm is provided with two blades or jaws disposed side by side and the innermost jaw projects closer to the opposed jaw of the other arm than does the outermost jaw. The outermost jaw is the "go" jaw and the innermost jaw is the "no go" jaw. For example, if a part to be gaged is accurate within its permissible limits such part will pass into the space between the "go" jaw and the opposing jaw of the other arm but will not pass into the space between the "no go" jaw and the opposed jaw of the other arm.

The instant invention pertains to the particular type of gage disclosed in my copending application No. 579,807, filed February 26, 1945. In such application the jaws are mounted within guide ways for adjustable slidable movement transversely of the arms toward and away from each other. This adjustable slidable movement is accomplished by the manipulation of a screw which is disposed substantially within the thickness of the arm between the adjustable jaw and the arm. The screw is operable through an opening in the arm at one end of the jaw supporting guide way. The jaw is held at adjusted positions within the guide way by a second screw. This second screw is disposed substantially entirely within the thickness of the arm and extends transversely thereof and is accessible for tightening or loosening of the jaw through an opening in the frame on the face opposite that face on which the jaw is mounted.

In the instant invention, a separate cover plate is provided for a part of each arm. This cover plate is secured to the arm and covers both of the openings through which the two separate screws above described are accessible. This cover plate protects both of the screws from unauthorized tampering or accidental shifting which might loosen or interfere with the adjustment of the jaws.

In the specific embodiment of the gage herein disclosed, one arm is provided with a single jaw member and the opposite arm is provided with a pair of jaw members. The two jaws of the pair are disposed side by side in opposition to

the single jaw. Each of the three jaw members is independently adjustable through manipulation of its own adjustment screw. Each jaw member is held in its own retaining screw at any adjusted position. One cover plate is provided for the adjusting screws and retaining screws of the two jaw members which are mounted side by side. Another cover plate is provided for the adjusting screws and retaining screws of the single jaw member.

Other objects, advantages and meritorious features will more fully appear from the following specification, claim and accompanying drawing wherein:

15 Fig. 1 is a plan of a gage embodying this invention with one cover plate partly broken away.

Fig. 2 is a transverse sectional view taken on the line 2—2 of Fig. 1, but showing the broken away cover plate complete and in place.

20 Fig. 3 is a sectional view taken on the section line 3—3 of Fig. 1.

Fig. 4 is a sectional view taken on the section line 4—4 of Fig. 1.

25 Fig. 5 is a perspective of one of the jaws or gage blades.

The gage frame is generally U-shaped in outline as shown in Fig. 1. It comprises a frame indicated generally by the numeral 10 and having a pair of arms 12 and 14 respectively. Each of these arms is provided with a guide way for one or more gage jaws. These two guide ways extend transversely across one face of each arm. The two guide ways are in direct opposition to each other. The arm 12 is shown as having a guide way 16 within which a jaw 18 is supported for slidable movement transversely of the arm. The arm 14 is provided with a guide way 20 within which are mounted side by side a pair of gage blades or jaws 22 and 24. These jaws 22 and 24 are supported for independent slidable movement within the guide way toward and away from the jaw 18 of the other arm. The jaws are of such thickness and the guide ways of such depth that the jaw comes out flush at least (and is here shown as extending beyond) the face of the arm within which the guide way is formed. The jaws are shown at their gaging edges as of slightly increased thickness as indicated by the numeral 25.

As hereinabove stated this gage is of the "go" "no go" type. The jaw 24 which is the innermost jaw is shown as projecting closer toward the jaw 18 than is the jaw 22. The jaw 24 would be the "no go" and the jaw 22 would be the "go" jaw. Each jaw is adapted to be held at its position of adjustment with respect to its opposed

jaw by one or more retaining screws. The large jaw 18 is shown as held by two retaining screws 26. Each retaining screw has a head portion which seats within the countersunk portion 28 of a slot 30 through which slot the screw extends to enter the jaw 18. These two screws 26 are threaded into the jaw 18. It is apparent that when they are tightened the jaw is drawn to the bottom of the guide way and held securely at such place. These slots 30 are shown as extending lengthwise of the guide way and Figs. 1 and 3 illustrate this arrangement.

In Fig. 4, the two jaws 22 and 24 are shown as each provided with a retaining screw. The jaw 22 is provided with retaining screw 32; the jaw 24 is provided with retaining screw 34. Screw 32 has a head 36 which seats within a countersunk portion 38 of a slot 40. This slot 40 extends lengthwise of the jaw 22 and opens into the guide way 20. This screw 32 is adapted to draw the jaw to the bottom of the guide way to secure it at any position of adjustment within the guide way. The screw 34 has a head 42 which is adapted to seat within a countersunk portion 44 of a slot 46. The slot 46 extends transversely through the arm and opens into the guide way 20. The screw 34 when tightened draws the jaw 24 to the bottom of the guide way and holds it at any position to which it is adjusted.

Each jaw is also provided with an adjustment screw. In this particular construction, each jaw is shown as adjustable. One of these adjustment screws is shown in dotted outline in Fig. 1 but they are all shown in solid line in Figs. 2, 3 and 4. The jaw 18 is provided, for example, with an adjustment screw 48. This adjustment screw 48 is disposed entirely within the width of the arm 12 as shown in Fig. 2. Underneath the guide way 16 the arm is provided with a recess 50 which extends lengthwise of the guide way. This recess is of a depth to receive the head 52 of the screw 48. Such head has such a diameter however that it projects into the guide way space and it is there engaged within a slot 54 formed in the underside of the jaw 18 as shown particularly in Fig. 2. The screw is threaded into an internally threaded opening 56 in the arm so that as the screw is threaded in or out it moves the jaw 18 in or out and toward and away from the jaws of the other arm.

Underneath each jaw of the other arm there is an adjustment screw. The jaw 24 is provided with an adjustment screw 58; the jaw 22 is provided with an adjustment screw 60. Screw 58 is disposed within a recess 59 underneath jaw 24. Screw 60 is disposed within a recess 61 underneath jaw 22. Each adjustment screw 58 and 60 is provided with a head which serves the same function as the head described on the adjustment screw 48. The adjustment screw 58 has a head 62 which is received within a recess 59 formed underneath the guide way 20 and which is engaged within a slot 66 formed in the underside of the jaw 24 as shown in Figs. 2 and 5. The screw 60 has a similar head which functions in a similar manner in connection with jaw 22.

Generally speaking, the construction hereinabove described is similar to that disclosed and claimed in my copending patent application Serial No. 579,807 filed February 26, 1945. In such copending application I show cover plates over the heads of the adjustment screws. In this application I have provided a different kind of cover plate which serves more completely to protect not only the adjustment screws but the jaw retaining

screws against unauthorized tampering or accidental dislocation. I provide a cover plate for each arm which cover plate may be formed of sheet metal or the like and is of a right angle contour in sectional outline.

The arm 12 is provided with a cover plate 70 which is L-shaped in cross section. One flat angular portion 72 of this cover plate 70 is adapted to overlie the slots 30 of the retaining screws 26 and 26. This cover plate 70 is held in place by a screw 74 which is threaded into the arm between the two slots 30. This cover plate has another angular portion 76 which is adapted to overlie the opening to the recess 50 within which the head of the adjustment screw 48 is disposed so that not only is the adjustment screw covered by the cover plate but the retaining screws are likewise covered.

The arm portion 14 is provided with a cover plate 80 which has one angular portion 82 which covers the securing screws 32 and 34 and slots 40 and 46 through which said screws extend. This cover plate has another angular portion 84 which covers the recess within which adjustment screws 58 and 60 are disposed so as to protect these adjustment screws as well as the retaining screws from dislocation or tampering. This cover plate 80 is held in place by a screw 86 as shown in Fig. 2.

What I claim is:

A gage comprising a U-shaped frame the arms of which are provided with opposed transversely disposed gage jaws, one arm being provided with a transverse guide way disposed in its side face, said arm having a bore extending transversely therethrough parallel to said guide way and in superposed relation thereto, the bore being counterbored from the outer side of said arm throughout a portion of its length, the radius of the counterbore being greater than the distance from the center of said bore to the bearing surface of the bottom of said guide way whereby the counterbore throughout its length communicates with the bottom of the guide way and forms a slot therein, said bore being internally threaded along the remainder of its length, an adjusting screw received within the threaded portion of said bore having a head conforming to the size of the counterbore and received therein whereby said head projects through said slot into the bottom of said guide way, a jaw slidably mounted in said guide way, means for retaining the same therein, said jaw having a transversely disposed groove adjacent one end receiving the head of the adjacent screw whereby rotation of the same moves the jaw along the guide way, and a cover plate which is L-shaped in sectional outline detachably secured to each arm with one angular portion of the plate overlying the outer edge of the arm and covering the opening of the counterbore and the adjacent screw head disposed therein, said jaw retaining means comprising a slot in the frame arm extending in the direction of jaw movement and communicating with the bottom of the guide way, together with a headed screw extending through said slot and threaded into an opening in the jaw, and the other angular portion of said cover plate covers the slot in the frame arm and the screw head disposed therein.
